UNITED STATES PATENT OFFICE.

JOHN HENRY MUNDERLOH, OF PHILADELPHIA, PENNSYLVANIA, ASSIGNOR
TO LOUIS WEBER, OF SAME PLACE.

SLIDING DOOR.

SPECIFICATION forming part of Letters Patent No. 575,162, dated January 12, 1897.

Application filed March 8, 1894. Serial No. 502,831. (No model.)

To all whom it may concern:

Be it known that I, JOHN HENRY MUNDERLOH, a citizen of the United States, residing in the city of Philadelphia, State of Pennsylvania, have invented certain new and useful Improvements in Sliding Doors, of which the following is a full, clear, and exact description, reference being had to the accompanying drawings, forming a part of this specification.

My invention relates to sliding doors, and has for its object to provide a pair of doors and actuating and guiding devices therefor so operating that by grasping the handle of either door they will both be slid at the same time laterally to or from each other.

With this object in view the invention consists in the novel construction and combination of parts, all as hereinafter described, and 20 pointed out in the appended claim.

In the drawings illustrating my invention, Figure 1 is a front elevation of a door-frame, a pair of sliding doors, and actuating and guiding devices, the drawing showing the 25 doors closed. Fig. 2 is a like view of the same parts, showing the doors open.

My improvements are applicable to all sliding doors, but more particularly to street-car doors. The drawings show the door-frame of 30 a car, (marked A.) A pair of parallel guide-bars of unequal length (marked a a') are provided, secured to the frame of the door at a a' , and have downwardly-projecting ends a^2 , secured to the door-frame at a^3 , which serve 35 as stops to limit the lateral movement of the doors, although one only of said stops is essential for that purpose. The lower of these two guide-bars (marked a^4) extends inwardly only as far as the pinion hereinafter described.

40 Said lower bar a^4 serves as a guide to one door B and its rack-bar b , while the opposite guide-bar a serves as a guide to the opposite door (marked B') and its rack-bar b' . A pinion-wheel C is fixedly secured to the frame at or 45 about a point above the junction of the inner vertical edges of the two doors, which is also at or about the end of the toothed portion of the two rack-bars, and this pinion-wheel meshes with both rack-bars, and the three 50 may be more securely held in proper relative position by an overlapping plate c, if desired.

A projection b^3 may be added to the rack-bar b' the width of the distance between said bar and the guide a^4 to steady the reciprocatory movement of the said bar. Other overlapping 55 brackets a^5 may be provided, but are not essential, to prevent any possible lateral or outward movement of the rack-bars relatively to the pinion-wheel.

The doors may each be provided with handles b^3 b^5 or other appropriate means whereby to grasp them by the hand of the operator. Preferably a guide-slot D is provided in the base of the frame to steady the lateral movement of the doors.

60 The principle of construction of the invention is in providing two parallel rack-bars, arranged one above the other, carried by a pair of doors, said bars extending inwardly in opposite directions to each other beyond the 65 inner vertical edge of the doors, and an independently-fixed pinion-wheel arranged centrally between the said parallel rack-bars, with means to guide and maintain the same in mesh therewith. I do not, however, claim 70 broadly such means for operating a pair of doors, as similar devices have heretofore been patented. The particular arrangement, however, of the rack-bar and guides as herein specified and as shown, whereby the doors in 75 operation are made to move in true horizontal lines and are held from vertical vibration, I believe to be new.

80 The operation of the device is as follows: When the door B', for illustration, is grasped 85 by its handle b^3 and moved laterally away from its contiguous door D, its rack-bar b' will rotate the pinion-wheel C, and thus actuating the opposite rack-bar b cause it to reciprocate the door D in the opposite direction to that 90 in which the door B' is, by this movement of the parts, simultaneously moving. During this operation the rack-bar b moves on the guide-bar a^4 and the rack-bar b' and its projection b^3 move in contact with the guide-bar 95 a , whereby the doors are compelled to move in true horizontal lines, as above specified.

Having thus described my invention, what I claim as new, and desire to secure by Letters Patent, is—

100 The combination with a pair of sliding doors, and a frame upon and against which the same

are mounted, of a pair of guide-bars a a' secured to said frame above the door, one above the other, one of said guide-bars extending above and beyond both doors, and the other 5 extending above and beyond one only of said doors, a rack-bar b secured to the upper edge of one of said doors below and in contact with the guide-bar a' and extending over the other door, a rack-bar b' secured to said other door 10 and extending beyond its inner edge above the first rack-bar, in contact with the guide-bar a' , and having also a guide projection in contact with the bar a' , a pinion-wheel fix-

edly secured to the frame centrally between the two rack-bars, means for maintaining said 15 rack-bars in proper register with said pinion, and a stop or stops carried by the guide-bars for limiting the movement of said doors, substantially as described.

In testimony whereof I have hereunto affixed my signature this 27th day of February, A. D. 1894.

JOHN HENRY MUNDERLOI.
